UNITED STATES PATENT OFFICE

1,996,967

BATTERY TERMINAL PULLER

Richard J. Kratky, Boise, Idaho

Application June 12, 1934, Serial No. 730,320

4 Claims. (Cl. 29—85)

The invention aims to provide an exceptionally simple and inexpensive, yet an easily operable and efficient tool for pulling battery terminals from terminal posts or performing similar work, 5 the tool being so constructed that its use will place no strain upon the battery case, cells or plates even though a terminal being pulled has become badly corroded, and therefore very tenaciously connected with the terminal post.

10 With the foregoing in view, the invention resides in the novel subject matter hereinafter described and claimed, description being accomplished by reference to the accompanying drawing.

15 Fig. 1 is a side elevation partly in section showing the tool in use.

Fig. 2 is an edge view.

Fig. 3 is a perspective view showing one of the terminal gripping jaws.

20 Fig. 4 is a perspective view showing the cross head with which the upper ends of the jaw carrying levers are connected.

A preferred construction has been shown and will be specifically described, with the understanding however that within the scope of the 25 invention as claimed, minor variations may be made.

The tool comprises two levers 5 fulcrumed together at 6 between their ends, the lower ends 30 of said levers being provided with terminal-engaging jaws 7. Each of these jaws preferably includes a lip 8 to extend under the terminal T, and a vertical toothed jaw face 9 to abut the outer side of the terminal. The upper ends of the 35 levers 5 are provided with converging slots 10, and by means of pins 11 passing through said slots, said levers are connected with a cross head 12. Threaded through this cross head is a manually operable screw 13 whose lower end 14 is 40 pointed or otherwise adapted to abut the terminal post P, the upper end of said screw being shaped at 15 to engage a wrench or the like.

To operate the tool, the screw 13 is loosened sufficiently to allow engagement of the jaws 7 45 with the terminal T with the screw disposed at the upper end of the terminal post P. The screw 13 is then tightened with the result that the cross head 12 moves upwardly and the co-acting slots 10 and pins 11 swing the levers 5 about their 50 fulcrum 6 to tightly hold the jaws 7 engaged with the terminal, the further upward movement of the cross head 12 after jaw and terminal engagement, serving to lift the levers 5, thereby pulling the terminal from the post. All strains incident 55 to operation of the tool are centered upon the

terminal and the terminal post and there is therefore no danger of injuring the battery case, cells or plates.

In the preferred construction, the two levers 5 cross each other and are fulcrumed together at their crossing point, and when this construction is followed, the slots 10 must converge downwardly. These slots may be slightly curved as shown.

While it is possible that the levers 5 could be 10 formed otherwise than of the exact shape herein shown, this shape is preferred and it will be observed that both of said levers are suitably offset at 16 to clear the screw 13.

It is preferable that the cross head 12 consist 15 of a central collar 17 through which the screw 13 is threaded, and two pairs of rigid arms 18 integral with said collar and projecting in opposite directions therefrom, said pairs of arms straddling the upper ends of the levers 5 and carrying the pins 10.

20 It will be seen from the foregoing that a novel and advantageous tool has been provided for carrying out the object of the invention, and attention is again invited to the possibility of 25 making variations within the scope of the invention as claimed.

I claim:—

1. A battery terminal puller comprising two levers fulcrumed together between their ends 30 and having terminal-engaging jaws at their lower ends, the upper ends of said levers being provided with converging slots, a cross head having pins passing slidably through said slots respectively, and a manually operable screw 35 threaded through said cross head, the lower end of said screw being adapted to abut the terminal post.

2. A battery terminal puller comprising two crossed levers fulcrumed together at their crossing point and having terminal-engaging jaws at their lower ends, the upper ends of said levers being provided with downwardly converging slots, a cross head having pins passing slidably through said slots respectively, and a manually operable screw threaded through said cross head, the lower end of said screw being adapted 40 to abut the terminal post.

3. A battery terminal puller comprising two levers fulcrumed together between their ends and having terminal-engaging jaws at their lower ends, the upper ends of said levers being provided with converging slots, a collar between 45 said upper ends of said levers having pairs of 50

rigid arms which straddle the same, pins passing through said rigid arms and through said slots, and a manually operable screw threaded through said collar, the lower end of said screw being adapted to abut the terminal post, said levers being offset to clear said screw.

4. A battery terminal puller comprising two crossed levers fulcrumed together at their crossing point and having terminal engaging jaws at their lower ends, the upper ends of said levers

being provided with downwardly converging slots, a collar between said upper ends of said levers having pairs of rigid arms which straddle the same, pins passing through said rigid arms and through said slots, and a manually operable screw threaded through said collar, the lower end of said screw being adapted to abut the terminal post, said levers being offset to clear said screw.

RICHARD J. KRATKY.
